UNITED STATES PATENT OFFICE.

EDGAR W. CLARKE, OF EVANSTON, ILLINOIS, ASSIGNOR TO AMERICAN TAR PRODUCTS COMPANY, OF CHICAGO, ILLINOIS, A CORPORATION OF DELAWARE.

APPARATUS AND PROCESS FOR BURNING FUEL.

Application filed October 13, 1922. Serial No. 594,380.

The object of this invention is to accomplish the employment as commercial fuel of pitch and other analogous carbonaceous materials which melt or liquefy when subjected initially to furnace temperatures.

In the distillation of tar for the production of chemical products and creosote, there remains a residue constituted essentially of pitch, which residue comprises about fifty to 10 seventy per centum of the original tar mass before its distillation. In spite of the fact that for many years past large sums of money have been expended for advertising and for development work to extend the uses 15 for pitch, the market has never heretofore been able to absorb the available supply. Moreover, the rapid development of by-product coke ovens has correspondingly increased the amount of tar to be marketed. 20 with the result that immense quantities of pitch have accumulated at the tar distilleries. Attempts have been made to employ this surplus pitch as fuel by liquefying it and introducing it in a liquid state into the 25 combustion chamber by burners analogous to those employed for fuel oil. Although pitch is high in carbon and, chemically, is a most excellent fuel, the employment of pitch in the liquid state as a substitute for 30 fuel oil has not met with success, because of the difficulties and complications encountered in maintaining the pitch in a fluid state at the required temperature. It has also been proposed to pulverize the pitch 35 and employ it as a substitute for pulverized coal in pulverized coal burners. But the prior attempts to employ pulverized pitch in existing burner devices have not been successful, for the reason that the section of the 40 pipe or burner delivering the pitch into the furnace became heated by radiation from the furnace, with the result that temperatures were developed that softened and made particles of pulverized pitch to adhere to 45 the inner surface of the delivery pipe or burner. This action resulted in the accumulation of a coke-like mass which seriously interfered with the delivery of the pulverized fuel to the furnace and eventually completely choked up the burner or delivery pipe. 50 By the present invention, the employment of pulverized pitch as fuel is successfully accomplished without permitting the pitch to soften or melt in the delivery nozzle or pipe, so that accumulations which

choke the nozzle are altogether eliminated and a continuous delivery of the pitch to the furnace may be effected.

In addition to the general objects recited above, the invention has for further 60 objects such other improvements or advantages in operation and results as may be found to obtain in the structures and processes hereinafter described or claimed.

In the accompanying drawings forming a 65 part of this specification and showing for purposes of exemplification a preferred form and manner in which the invention may be embodied and practiced, in conjunction with one well known type of furnace 70 construction, but without limiting the claimed invention specifically to such illustrative instance:

Figure 1 is a vertical section taken longitudinally through a furnace of ordinary 75 construction equipped with means for burning powdered pitch as fuel, constructed in accordance with the present invention.

Figure 2 is a horizontal section of the 80 parts illustrated in Fig. 1.

Figure 3 is an enlarged vertical section of the nozzle and fuel delivery portion at the 85 front of the furnace.

Figure 4 is a horizontal section of the parts shown in Fig. 3.

In its present embodiment, the invention is applied to an ordinary type of furnace. For convenience, the present description will be confined to the illustrated application of the invention to such a furnace. Features 90 of the invention are, however, applicable generally to furnace structures; consequently, the invention is not confined in its scope to the specific use and embodiment herein described as an illustrative example. 95

Referring to the drawings, there are illustrated views of a furnace of ordinary construction. The furnace is constituted of the usual main heating chamber 11, located beneath the boiler 12, and the front firebox 13 100 in which the fuel is burned. At its rear end, the firebox communicates with the main heating chamber 11 and, at its bottom, with the ash pit 14. The front wall 15 of the firebox is provided with a stoke hole 16 105 through which the fuel is introduced into the firebox. Preferably, the top of the stoke hole 16 inclines upwardly toward the interior of the firebox, as shown at 17 in Figs. 1 and 3, and the side walls diverge 110

toward the interior, as shown at 18 in Figs. 2 and 4. This construction provides a stoke hole in the front refractory wall of the furnace which is flared toward the firebox, so as to prevent impingement of any of the particles of solid fuel with the walls of the stoke hole, as said fuel particles pass into the firebox. The front of the stoke hole 16 is provided with a vertical plate 19 having a central inlet opening 20 made large enough to permit the jet of fuel to pass, without interference, into the firebox. In applying the invention to existing installations, the ordinary stoke hole door may serve as the vertical plate for the front of the stoke hole, by simply boring a hole in the door large enough to admit the jet of fuel.

According to the invention, the powdered pitch is delivered into the furnace, from a nozzle or nozzles, the delivery end of which terminates at a distance from the front face of the front wall of the furnace, so that the nozzle is located out of the zone of high temperature and overheating of the nozzle is avoided. The pitch is delivered by the nozzle in a stream at high velocity through the inlet 20 and stoke hole 16, the velocity being maintained high enough to keep the fuel in a compact stream until it reaches the combustion zone within the firebox, thus preventing the fuel from coming in contact with any part of the furnace at the point of entrance to which it might adhere if such contact be made. In other words, the fuel is introduced into the furnace at such a velocity that the particles will have reached the combustion zone in the firebox before the heat of the furnace can become effective to cause the particles to melt and adhere to the nozzle, or furnace surfaces. Consequently, any probability of the delivery nozzle becoming choked from agglomerated pitch or pitch coke deposits is practically eliminated. Moreover, as the nozzle is located entirely beyond the front wall of the furnace and out of the zone of high temperature, the delivery end of the nozzle is kept continuously below the melting point of the pitch. But even if the nozzle did become overheated, from long continued use, the velocity of the fuel stream would be great enough to carry the fuel into the firebox without deposits on the wall of the nozzle.

As shown in the drawings, the fuel delivery nozzle 21 is preferably sharply tapered toward the delivery end so as to cause the powdered pitch to issue from the spout 22 in a jet or stream of great force and confined laterally of the jet for a sufficient distance to keep the fuel stream compact until it reaches the combustion zone, so as to avoid impingement of the fuel particles with any part of the furnace structure at the point of entrance of the fuel. The powdered pitch is delivered to the nozzle

21 through a fuel pipe 23 and the fuel stream may be an admixture of powdered fuel with combustion supporting air or other gases. The fuel inlet 20 in the front of the furnace may be made large enough to permit the jet of fuel to draw along with it into the furnace sufficient air to support combustion of the fuel.

Any suitable means for imparting the high velocity to the fuel stream is within the purview of the invention. Mechanical devices or blowers having the requisite capacity may be employed. The drawing shows a pulverizer 24, the delivery end of which is connected to the fuel pipe 23, the pulverizer operating not only to pulverize the fuel but also to mix it with air for effecting efficient combustion and to deliver the admixture of pulverized fuel and combustion supporting air at high velocity through the pipe 23 to the nozzle 21. The sharply tapered nozzle 21 and its spout 22, which is greatly restricted in diameter in respect to the diameter of the pipe 23, serve to accelerate the already high velocity stream of fuel in the pipe 23, so that a powerful jet issues from the spout 22. The lump pitch may be deposited in the hopper 25 and conveyed by a chute 26 from the hopper to the inlet of the pulverizer.

In carrying out the present invention it has been found that a satisfactory operation of the furnace is obtained by employing from 50 to 60 cubic feet of air per pound of pitch, and a minimum jet velocity of 3000 feet per minute has served to maintain the pulverized pitch in suspension and prevent its becoming adherent prior to its reaching the combustion zone. It will be understood, however, that a satisfactory operation of the furnace may be obtained by varying these proportions and employing higher jet velocities at the point of entrance of the fuel.

The term pitch as employed in the foregoing specification and in the claims hereinafter made, includes any carbonaceous fuel which agglomerates when initially subjected to furnace temperatures. For example, the invention may be applied to such analogous materials as asphalt, mineral oil residues, resinous by-products, mineral pitch and other fuel materials which become soft and adherent when heated to relatively low temperatures. Pitch, for example, has a melting point not exceeding 400° F., and carbonaceous materials having similar low melting points are contemplated by the invention.

The invention as hereinabove set forth may be variously embodied within the scope of the claims hereinafter made.

I claim:

1. The method of feeding pulverized pitch to a furnace which consists in feeding

the pulverized pitch in a stream of such velocity that the fuel is maintained in a compact stream at the point of entrance into the furnace, releasing the fuel from its feeding means while the fuel is outside of the furnace, and entraining a surrounding annulus of air with said stream, whereby the fuel reaches the combustion zone before it can become adherent, substantially as specified.

2. Apparatus for burning pulverized pitch comprising, in combination: a furnace having an unenclosed fuel inlet in its front wall; means including a nozzle for feeding such pitch in a blast through said nozzle to said furnace, said means and said nozzle being located entirely outside of said furnace and positioned with respect to the inlet in the front wall of the furnace so that the delivery end of said nozzle terminating opposite said fuel inlet is on the outside of the front wall of said furnace and at a substantial distance from the outer surface of the said front wall and with a vertically extending free space therebetween; whereby the pitch being ejected from said nozzle is by such air-space insulated from being rendered sticky by the furnace heat until after such pitch is projected through said inlet.

3. Apparatus for burning pulverized pitch comprising, in combination: a furnace having an unenclosed fuel inlet in its front wall; means including a delivery nozzle for

feeding such pitch in a blast through said nozzle to said furnace; said means and said nozzle being located entirely outside said furnace and positioned with respect to the fuel inlet in the front wall of the furnace so that the delivery end of said nozzle opposite the fuel inlet does not extend to the plane of the outer surface of the front wall of the furnace and does not extend into the fuel inlet; whereby the pitch being ejected from said nozzle is by such air-space insulated from being rendered sticky by the furnace heat until after such pitch is projected through said inlet.

4. In the feeding of pulverized pitch to a furnace the improvement which consists in: delivering it with a blast at the point of entrance into said furnace at such a velocity as to maintain the stream against dispersing while entering said furnace, and releasing the stream from its feeding means while the pitch is outside of the outer surface of the furnace wall and substantially insulated therefrom by an air-space; whereby the pitch leaves the feeding means at a region where the temperature from radiation is not high enough to effect adherence to the feeding means of particles of pitch that are still within the feeding means.

In testimony whereof I have hereunto set my hand.

EDGAR W. CLARKE.
